UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

FLUID-OPERATED PERCUSSIVE TOOL.

1,343,610.

Specification of Letters Patent. Patented June 15, 1920.

Application filed August 30, 1919. Serial No. 320,909.

To all whom it may concern:

Be it known that I, LEWIS C. BAYLES, a citizen of the United States, residing at Easton, in the county of Northampton and 5 State of Pennsylvania, have invented a certain new and useful Improvement in Fluid-Operated Percussive Tools, of which the following is a specification.

This invention relates to a fluid operated 10 percussive tool, and in particular to a fluid operated tool having a piston of two diameters and adapted to strike a drill steel or other tool at the end of its forward stroke.

The objects of the present invention are to 15 improve the operation of percussive tools of the above type, to make their operation steadier, easier to start and to prevent dead-centering.

A further object of the invention is to provide 20 means to continue the admission of fluid to one end of the cylinder after the main admission port is closed, to increase the mean effective pressure in that end, thus increasing the force to return the piston to its initial 25 position.

With these and other objects in view my invention consists in the features of construction and operation set forth in the following specification.

30 Referring to the drawings attached hereto and forming a part of this specification.

Figure 1 shows a longitudinal view in section of a percussive tool provided with the present invention.

35 Figs. 2, 3 and 4 are, respectively, sections taken on lines 2-2, 3-3 and 4-4 of Fig. 1.

Fig. 5 shows diagrammatically the cylinder and piston of a drill made in accordance with the present invention, the piston being 40 shown at the beginning of its forward stroke.

Figs. 6, 7 and 8 are diagrammatic views similar to Fig. 5, with the piston in different positions of its stroke.

In percussive tools and especially in percussive drills used in rock drilling, it is usual 45 to provide means to rotate the drill steel simultaneously with the reciprocation of the piston, and in many of the drills as now used the rotation parts are so applied that during 50 the striking blow of the piston, the piston is free and simply has to turn a very light and easily rotated part of the rotating mechanism, but on its reverse or upstroke the piston is rotated a part of a revolution and the

front chuck and drill steel also similarly 55 rotated. Operating the rotation in this manner does not lessen the striking power or blow of the piston materially but is open to a possible objection that in the event of the upstroke of the piston not being powerful 60 enough, the rotation will not operate.

The present invention relates particularly to a construction admitting of a very powerful upstroke which can be utilized to advantage in increasing the power of the rotation. 65 The effect of a more powerful upstroke may also be noticeable in increasing the number of blows per minute by reason of the fact that the more powerful upward stroke quickens the speed of the upward stroke. 70 The downward or power blow of the piston is in no way affected by the present invention.

Referring now more particularly to the drawings, 1 refers to the cylinder, 2 a piston operated therein, having a head 3 and a 75 shank portion 4 at its rear end. The forward end of the piston is fluted as shown at 5 forming flutes 5 by means of which it is non-rotatably and slidably attached to the chuck 6. The piston head 3 operates in the forward 80 bore 7 of the cylinder 1 and the shank 4 within a bore 8 of smaller diameter. The piston shank 4 is suitably bored and rifled to take the rifled member 25 having spiral flutes 26 engaging corresponding grooves in 85 the rifled portion of the shank 4. The rear end of the rifled member 25 is provided with a head 27 in which is located a spring pressed pawl 28. In alignment with this head 27 is a notched member 29 set into a back head 30 90 so that movement of the piston on its forward stroke rotates the rifled member 25 and permits the pawl to slide over one or more notches in the member 29 but on its rear movement is forced to rotate itself and thereby rotate the chuck 6 and drill steel 6^a, the pawl meanwhile engaging one of the notches and preventing retrograde movement of the rifled member 25.

Motive fluid, usually compressed air or, in 100 some instances steam, enters orifice 9 from any suitable source and, passing through conduit 10 to the rear of cylinder bore 8 exerts a constant pressure against the rear end of the shank 4. The conduit 10 is also 105 has an orifice as shown at 11 at a point near the forward end of the bore 8 so that when the piston is in the rear end of the cylinder,

2

a passage is opened by neck 12 of the piston to admit motive fluid to the rear end of the cylinder bore 7. A conduit 13 has an orifice 14 as shown about midway of the bore 8 of the cylinder at its rear end, the other end being at the forward end of bore 7 so that when the piston is in the forward end of the cylinder, a passage is opened for the supply of motive fluid to the front end of the cylinder bore 7. All of these parts, including the conduit 13, are similar in every respect to my construction shown and described in Patent No. 1,268,081 granted June 4, 1918. Preferably the present construction 15 may be provided with a supplemental exhaust mechanism comprising a valve 16 opening and closing conduits 17 and 18 at the ends of the cylinder bore 7. The common central exhaust port 19 is also applied 20 as is usual in this form of tool. This method of exhausting the fluid from the cylinder is similar in every way to that described in Patent No. 1,278,287 granted Sept. 10, 1918, and will therefore require no further description.

It will be seen from the above description that no fluid is admitted to the forward end of the cylinder 7 until the rear end of shank 4 passes or overruns the orifice 14 of the 25 conduit 13 and then as soon as this orifice 14 is closed on the reverse movement of the piston 2 no additional fluid will be supplied. It is therefore an object of the present invention to provide means to continue the supply of fluid to the forward end of cylinder bore 7 until the piston 2 has made a larger portion of its reverse stroke, thus increasing the pressure within the forward end of bore 7 to force the piston rearwardly 30 and prevent it from slowing up or stopping. This means comprises an extra or auxiliary conduit 20, its rear orifice opening into bore 8 of the cylinder being at point as shown at 21 which is about three-fourths 35 the total length of the bore 8 from its forward end. This conduit 20 is shown intercepting a convenient point in the conduit 13. In operation of the piston which will be clearly evident from inspection of Fig. 5 40 et seq. as soon as the piston 2 on its forward stroke indicated by the arrow in Fig. 5, passes the orifice 21, a slight amount of fluid is allowed to pass into conduit 13. The amount passing, however, is not sufficient to 45 materially increase the amount of fluid supplied during the down stroke of the piston. Especially is this so because the forward stroke of the piston being free from any drag on the rotation parts is very rapid and 50 the instant of time during which the conduit 20 is open before the main conduit 13 is open is very trifling. During this forward stroke the slight amount of fluid supplied through conduit 20 passes from the forward end of 55 bore 7 through conduit 17 and past valve 60 16 which is in the position shown in Figs. 1 and 5. During the rear stroke, however, which as above indicated, is slower than the forward stroke, due to the drag and pull of the rotation parts, the time during which 70 the conduit 20 remains open and supplying fluid to the forward end after the main port of the conduit 13 is closed is very material and effectively increases the power and speed of the rear stroke of the piston. The 75 harder the rotation pulls or drags on the piston the slower will be the up or rear stroke of the piston and thus a longer time will elapse for fluid to pass through conduit 20 into the forward end of bore 7. In practice it has been found that the power of the rear stroke of the piston has been so greatly increased by the inclusion of conduit 20 that the rotation parts will have approximately four times the power compared 85 with the power when operating without the auxiliary conduit 20.

Referring again to Figs. 5 to 8 the proportions of the cylinder bores and the relative position of the ports and conduits for the supply and exhaust of motive fluid will be clear. Starting with the piston at the beginning of its stroke as shown in Fig. 5, motive fluid is supplied at constant pressure to the rear face of the shank 4 throughout the entire stroke of the piston 2, and also for a portion of the forward stroke is supplied to the rear of bore 7 of the cylinder. The port 21 opens when the piston has made between one fifth and one fourth of its 90 stroke and approximately simultaneously therewith the port 11 closes thus cutting off the supply of fluid to the rear of bore 7 of the cylinder (see Fig. 8).

As above indicated the amount of fluid supplied to conduit 13 and to the forward end of bore 7 during the rapid forward stroke of the piston is relatively small and serves only to increase slightly the air consumption but does not cushion the blow of 105 the piston 2 upon the drill steel 6 as this fluid may pass out through conduit 17. During the rear stroke of the piston, however, which as above stated is much slower than the forward stroke due to the drag of 110 the rotation parts, the port 21 is open for a longer period of time so that a much larger amount of fluid passes through conduit 20 and into the forward end of the bore 7. This has the effect of continuing the 115 supply of fluid to the forward end of bore 7 after the main supply has been cut off by the shank 4 overrunning port 14. As shown in Fig. 8, this port 21 remains open approximately until the central exhaust port 19 120 opens so that a supply of fluid to the forward end of the bore 7 is maintained throughout nearly the entire rear stroke of the piston 2.

Without the conduit 20, if the drag of the 125

rotation on the piston 21 stops it after the port 14 is closed the pressure of the fluid in the forward end of bore 7 falls materially due to leakage and the piston remains at rest. With the conduit 20, if the piston should come momentarily to rest the pressure in the forward end of bore 7 would gradually build up, thus forcing the piston rearwardly until the central exhaust port 19 opens and the supply port 11 opens when the piston would strike another blow. Furthermore without conduit 20 the piston may dead center or stop at any position on its back stroke between the closing of port 14 and the opening of port 19 while with conduit 20 the only position at which the piston can dead center is on a line where the conduit 20 is just closing and port 19 is just opening, this condition being almost impossible to produce.

The above description covers but one exemplification of the invention and it is to be understood that it is illustrative only and not limiting or restrictive of the invention.

Having thus described my invention, what I claim is:

1. In a fluid operated percussive tool, a cylinder having a bore of two diameters, a piston therein having portions fitting both diameters of said cylinder, said piston having a constant pressure area and two variable pressure areas, and means comprising a small port near the rear end of the smaller diameter portion of the cylinder and a larger port about midway of the smaller bore of the cylinder and overrun by the constant pressure area of the piston to admit

pressure fluid to force the piston in one direction.

2. In a fluid operated percussive tool, a cylinder having a bore of two diameters, a piston therein having portions fitting both bores of the cylinder, said piston having two pressure areas to drive it forwardly and one to return it, larger and smaller ports intercepting a constant pressure chamber of the cylinder and overrun by one end of said piston to convey fluid pressure to the forward end of the cylinder to return the piston, the smaller of said ports being located rearward of the larger port and remaining open approximately until the exhaust port opens, to maintain the pressure at the front of the piston to prevent the piston slowing up or stopping.

3. In a fluid operated percussive tool, a cylinder having a bore of two diameters, a piston therein having portions fitting both diameters of said cylinder, said piston having a constant pressure area and two variable pressure areas, and means comprising a main port and a small leak port spaced apart longitudinally of the smaller bore of the cylinder and overrun by the constant pressure area of the piston to admit pressure to force the piston in one direction, the small leak port being the port first opened and last closed by the piston, whereby pressure is built up at the front end of the piston in case the piston slows up or stops.

In testimony whereof I have hereunto set my hand.

LEWIS C. BAYLES.
